US0D1082959S

(12) **United States Design Patent** (10) **Patent No.:** **US D1,082,959 S**
(45) **Date of Patent:** **** Jul. 8, 2025**

(54) **SHAPE-TRANSFORMING TOY**

(71) Applicant: **Guangdong Yangbang Science and Technology Industry Co., Ltd.**, Shantou (CN)

(72) Inventor: **Jianwei Chen**, Shantou (CN)

(73) Assignee: **Guangdong Yangbang Science and Technology Industry Co., Ltd.**, Shantou (CN)

(**) Term: **15 Years**

(21) Appl. No.: **29/887,424**

(22) Filed: **Mar. 21, 2023**

(30) **Foreign Application Priority Data**

Nov. 23, 2022 (CN) 202230784502.3

(51) **LOC (15) Cl.** **21-01**

(52) **U.S. Cl.**

USPC **D21/579**
